CLAIM

The ornamental design for a Garlic Press, as shown and described.

DESCRIPTION

FIG. 1 is a bottom-left-front perspective view of a first embodiment of a garlic press showing my new design; FIG. 2 is a left side elevational view thereof; FIG. 3 is a right side elevational view thereof; FIG. 4 is a top plan view thereof; FIG. 5 is a bottom plan view thereof; FIG. 6 is a front elevational view thereof; FIG. 7 is a rear elevational view thereof; FIG. 8 is a bottom-left-front perspective view of a second embodiment of a garlic press showing my new design; FIG. 9 is a left side elevational view thereof; FIG. 10 is a right side elevational view thereof; FIG. 11 is a top plan view thereof; FIG. 12 is a bottom plan view thereof; FIG. 13 is a front elevational view thereof; and, FIG. 14 is a rear elevational view thereof.

The broken lines show portions of the garlic press and form no part of the claimed design.
